UNITED STATES PATENT OFFICE.

HENRY WILLIAM BARKER, OF ELBOW LAKE, MINNESOTA.

DRUG-MIXER.

SPECIFICATION forming part of Letters Patent No. 497,045, dated May 9, 1893.

Application filed July 30, 1892. Serial No. 441,643. (No model.)

To all whom it may concern:

Be it known that I, HENRY WILLIAM BARKER, a citizen of the United States, residing at Elbow Lake, in the county of Grant and State 5 of Minnesota, have invented certain new and useful Improvements in Drug-Mixers; and I do declare the following to be a full, clear, and exact description of the invention, such as will enable others skilled in the art to which it applies to make and use the same, reference being had to the accompanying drawings, and to the letters of reference marked thereon, which form a part of this specification.

My invention relates to improvements in 15 drug mixers, and although it is especially adapted for this purpose it may be used for other purposes if desired.

The object of my invention is the provision of an extremely simple, durable and efficient device of this character, and it consists of a device constructed substantially as illustrated, described and specifically claimed.

Figure 1 represents a perspective view of the device with one side broken away to more 25 clearly show the details of the device, and Fig. 2 represents a sectional view of a modified form of the device.

Referring by letter to the drawings—A designates the vessel or receptacle for containing the drugs, which has the central depressed 30 rib B, to which on each side are hinged the covers C, and to one side of the receptacle is secured a bail D, provided with a handle E preferably of wood. The bottom of the ves-

sel is provided with a socket F in which is 35 mounted the shaft G, having the upper cranked end H provided with a handle J. To the shaft is fixed or formed the mixer K which consists of the horizontal part L, the two side pieces L^x the short uprights L' and the inclined upper pieces L^{xx}. In the modified form the side pieces are made in the form of a screw which has the effect of more thoroughly mixing the material as will be understood.

The device makes an efficient drug mixer but it may also be used for popping corn, roasting coffee or for any other purpose where it would serve effectively, and by reason of its extreme simplicity, cheapness and effectiveness it should prove useful.

I claim as my invention—

The herein described device, consisting of the vessel having the central rib, the covers hinged to said rib, the socket in the base of the vessel, the shaft mounted in the socket and central rib and having the handle, and the stirrer or agitator carried by the shaft and comprising the horizontal part, the side pieces the short uprights or lugs and the inclined pieces, all arranged as shown and described.

In testimony whereof I affix my signature in presence of two witnesses.

HENRY WILLIAM BARKER.
